UNITED STATES PATENT OFFICE.

HERMAN H. D. KLINKER, OF NEW YORK, N. Y.

DIRIGIBLE BOMBING AEROPLANE.

Application filed May 24, 1923. Serial No. 641,044.

To all whom it may concern:

Be it known that I, HERMAN H. D. KLINKER, a citizen of the United States, residing at New York city, borough of Manhattan, in the county of New York and State of New York, have invented certain new and useful Improvements in Dirigible Bombing Aeroplanes, of which the following is a specification.

10 This invention relates to aircraft and has particular reference to the general type of flying machines shown, described, and claimed in my co-pending application filed March 28th, 1923, Serial No. 628,183, and 15 over which this present invention is an improvement, the same being designed especially for military use and for such purposes as bombing, as distinguished from the conveyance of passengers or freight as referred to more particularly in the previous 20 application.

For the convenience of any reader of both specifications the principal parts of the present construction are indicated by reference 25 characters corresponding to similar parts of said previous case.

Among the principal objects of the present improvement are the following: to provide an aeroplane with a peculiar propulsion means in the nature of tubular passage-ways equipped with powerful blower fans for the forward traction of the machine, either in connection with or separate from traction propellers as set forth in the previous application, and to provide improved tubular passage-ways and powerful blower fans for assisting at least in the elevating or vertical control of the machine.

In the accompanying drawings in which 40 the several principal parts are referred to by like reference numerals,

Figure 1 is a plan view of the main parts of my improvement.

Fig. 2 is a front elevation of the same.

45 Referring now more specifically to the drawings I would describe briefly the principal parts similar to those in the parent application, to lay a basis for the special description of the improved features. The body 10 may be variously constructed and shaped and sub-divided if desired for the storage or conveyance of the ammunition or implements of warfare according to the purpose of the machine. Access may be had to the interior of the body over rails or steps 29 and through a door-way 30. Windows

are indicated at W, and these of course may be variously located as desired. 50 are vertically arranged power operated shafts upon which are mounted helicopter or lifting propellers 51. Traction propellers 53 are shown mounted at the front portion of the machine on shafts 54 driven from motors 55 suitably located in relation to hollow buoyant lifting and sustaining planes 56, 57, and 58 extending laterally across and from the sides of the body.

55 Lateral direction controlling means includes a rudder 65 swung from a vertical axis 66 and preferably through lines 67 extending along the body. Elevator planes are indicated at 69 above the uppermost main front plane 56, and toward the rear of the body are located one or more auxiliary planes 73. At the bottom of the machine are arranged traction shoes 33 having tires 37 and connected through hangers 40 as specifically set forth in the previous application, and at or toward the ends of the lowermost plane 58 are pontoons 75.

60 The vertical blower controlling means above referred to are indicated as including a plurality of vertically arranged cylindrical tubes 89 in which are located power operated blower fans 90. With these fans suitably driven the machine will be lifted or controlled in its vertical movements and by the reversal of the fans in one or the other of the tubes the vertical steering of the machine may be manipulated. It will of course 65 be borne in mind that the upper compartments of the body as well as the planes themselves are of hollow construction and charged with suitable buoyant gas such as helium or hydrogen.

65 The principal features of novelty of this specification are the horizontal tubes or passage-ways 92 located on opposite sides of the body and parallel to each other and to the longitudinal axis of the body. Each of 100 these passage-ways is indicated, especially in Fig. 2, as built about one-half into the contour of the body, and the other half on the outside thereof. In these passage-ways are mounted powerful blower fans 93 on shafts 94 driven from motors 95 mounted at any convenient place, as for instance, upon the top of the body. Belts 96 operate between the motors and the shafts. It is estimated that these fans of say ten feet in diameter when run at a speed of 209 R. P. M. 105 will displace through each of the passage- 110

ways 92 eighty-eight thousand cubic feet of air per minute, a condition which will powerfully influence the forward movement of the machine, whereby the operation thereof with respect to the enemy's position may be exceedingly rapid.

I claim:

1. In an aeroplane of the type set forth, the combination of a body, elevating and elevating controlling means co-operating therewith, a pair of cylindrical tubular passage-ways extending along the body on opposite sides thereof and built partially within the

contour of the body, powerful blower fans mounted in said passage-ways on horizontal 15 fore and aft axes, and means to control the rotation of the blower fans.

2. Mechanism as set forth in claim 1 in which the tubular passage-ways are two in number and mounted on the sides of the body on the same level and are built substantially one-half of each within the contour of the side of the body, while the other half is convexed outward therefrom.

In testimony whereof I affix my signature.
HERMAN H. D. KLINKER.
